C. E. HILTON.
RESILIENT ARCH SUPPORT.
APPLICATION FILED OCT. 8, 1917.

Patented Sept. 16, 1919.

Inventor:

Clement E. Hilton

By W. Steele Jackson,
Attorney

UNITED STATES PATENT OFFICE.

CLEMENT E. HILTON, OF WEST COLLINGSWOOD, NEW JERSEY.

RESILIENT ARCH-SUPPORT.

1,316,156.

Specification of Letters Patent. Patented Sept. 16, 1919.

Application filed October 8, 1917. Serial No. 195,241.

To all whom it may concern:

Be it known that I, CLEMENT E. HILTON, a citizen of the United States, residing at 328 Cattell Av., W. Collingswood, in the 5 county of Camden and State of New Jersey, have invented a certain new and useful Resilient Arch-Support, of which the following is a specification.

The purpose of my invention is to support 10 the arch of the foot without restricting its motion and, by an arrangement of springs, to effect normal exercise of the muscles.

A further purpose is to support the inner 15 side of the arch of the foot resiliently, while allowing the outer side of the foot to lie in its normal position, substantially in a plane extending from the heel along the outer side of the foot, this effecting a perfect balance and distribution of weight.

20 A further purpose is to make part of the resilient arch support movable or removable with respect to the rest, so as to facilitate separate bending of these parts.

A further purpose is to utilize leaf springs 25 for resilient support and distribute their bearing points to secure maximum efficiency and minimum weight.

A further purpose is to provide adjustment of spring support by adjusting the distance between the bearings of the leaves or 30 springs and the contiguous leaves or plates against which they rest.

Further purposes will appear in the specification and in the claims thereof.

35 I have preferred to illustrate my invention by but a single one among the various forms in which it may appear, selecting a construction which has proved in actual use to be practical, efficient and inexpensive and 40 which at the same time well illustrates the principles of my invention.

Figure 1 is a top plan view of the preferred embodiment of my arch support.

Fig. 2 is a side elevation of the structure 45 seen in Fig. 1.

Figs. 3 and 4 are sections upon lines 3—3 and 4—4 of the structure shown in Fig. 1.

Fig. 5 is a top plan view of an intermediate spring which I prefer to use.

50 Fig. 6 is a view corresponding with Fig. 1 but with the parts in different positions.

The outer side of the foot does not have an arch at all and requires no support nor assistance of any character, but should be 55 allowed to lie in its normal position substantially within the same plane as the outer

side of the heel and the side of the front part of the foot. Again, the arch itself is most desirably not "propped", but is best merely returned to its natural and proper 60 position after the depression due to resting the weight of the body upon the foot. My invention is based upon the recognition of these two facts. I prefer not to lift the outer part of the foot at the arch and provide 65 a resilient support intended to exercise the plantar muscles, at all times suiting the resilient pressure to the need and returning the arch to the position which it should occupy when at rest, without regard to the 70 position which it may have assumed during the pressure upon the foot.

In the drawings, similar numerals indicate like parts.

In the preferred form the leather top facing 75 pad 5 is of the usual shape and thickness, filling the rear portion of the bottom and inner side of the shoe from a point at the back of the heel to a beveled edge 6 in front of the instep. For purposes of rear- 80 wardly adjusting the arch I mark contour lines 7 to which the heel may be cut to alter the position of the arch support with respect to the foot.

Upon the under side of this facing I 85 mount a plantar support or plate 8, which I make of spring material, in order to secure the advantage of the resilience of the main or body portion thereof as a leaf spring, giving it bearing against another 90 plate or spring near its outer ends 9 and 10. The top is flared at its inner and upper edge and is preferably slotted at several points, such as 11, 12, 13 to prevent it from acting 95 as a flange to stiffen the body.

The holes 14 pass through both the metal and the leather and provide ventilation. The air beneath is pumped through them against the bottom of the foot.

The ends of the "plantar" plate or spring 100 are rested as at 15 and 16, upon an under spring 17, at points such as 18 and 19, far enough from the ends 20, 21 to permit spring action of the material of spring 17 both inside and outside of these resting points; and 105 the extreme outer ends of the spring 17 are turned slightly upwardly to make them slide freely upon the leather of the shoe.

Between the plantar or upper spring and the lower spring 17, I place a reinforcing 110 or intermediate spring 22, resting as at 23 and 24 against the lower spring 17 or

against adjusting devices carried thereby, the resting points being so located between the ends and the center on each side as to take full advantage of the spring action of 5 the lower spring 17. The central part of the intermediate spring bears on its upper side, as at 25, against the under side of the main body portion of the plantar spring.

- In order to secure additional adjustment 10 between the intermediate spring and the lower spring, I thread adjusting screws, such as 26 and 27 through the lower spring at the proper points. The most convenient and effective means of securing this threading 15 for the adjusting screws is to punch out the material of the spring 17 in the form of reinforced cups which offer a greater thickness for tapping than the original metal.
- 20 In fastening the parts together the leather and the plantar spring are rigidly secured to each other at the ends, as by rivets 28. A rivet 29 passes through the upper and lower springs and forms a pivot for the latter, by which it can be turned angularly 25 to the position seen in Fig. 6. Suitable spacing is given between the two springs at the rivet to allow for the intermediate spring which is notched at 30 to engage the 30 side of this rivet.

Latching mechanism is provided for retaining the under spring in the position with respect to the plantar spring as shown in Fig. 1. A convenient form of latch shown 35 in the figures comprises a projection 31 from the plantar spring which passes through a kerf or notch 32 in the intermediate spring and, in the position shown in Fig. 1, fits into a depression 33 in the upper side of the 40 under spring, frictionally locking the parts together, but permitting the under spring to be sprung laterally and then turned angularly to any desired extent. When in the position shown in Fig. 6, the intermediate 45 spring can be removed, bent and replaced, and the under and plantar springs are separately accessible for hand bending to any permanent contour required.

Copies of this patent may be obtained for five cents each, by addressing the "Commissioner of Patents, Washington, D. C."

Having thus described my invention, what I claim as new and desire to secure by Letters Patent is:

1. In an arch support, a pad adapted to engage the foot, an upper spring secured thereto, a lower spring pivoted to the upper spring to move angularly with respect thereto and an intermediate spring held in position against removal by the lower spring in its normal position, but removable in an abnormal angular position of said lower spring with respect to said upper spring. 50

2. In an arch support, a pad adapted to engage the foot, an upper member outlining the intended contour of the foot, a lower member of spring material pivoted thereto and a spring removably secured between the 55 two members, removable in one position of the lower member and retained in place in another position thereof.

3. In an arch support, a pad adapted to engage the foot, upper and lower springs 70 affording support thereto and an intermediate spring removably secured between the upper and lower springs.

4. In an arch support, a pad adapted to engage the foot of the wearer, a plurality of 75 springs supporting the pad and adjustable means located between the springs and forming effective engagement between them for varying the extent of spacing given said springs by changing the distance between 80 the springs at these points of effective engagement.

5. In an arch support, a pad adapted to engage the foot of the wearer, a member curved at the side to support the instep of 85 the wearer, a spring whose middle portion engages said member, a second spring against which the first spring is adapted to bear and adjustable connections between the two 90 springs varying the distance of the actual terminals of the first spring from the second spring.

CLEMENT E. HILTON.
